EXTENSION DEVICE FOR BRACELETS
OR THE LIKE

Anthony R. Saccoccio, Cranston, R. I.

Application December 7, 1948, Serial No. 63,944

2 Claims. (Cl. 24—71)

2

This invention relates to an extension device for bracelets and the like for enlarging the encircling sizes of the bracelet so that the same may be passed over the hand of the wearer without separating the ends of the bracelet.

Various chain extension devices have been provided which have some extensibility either by reason of a resilient action to permit endwise sliding of the parts or by reason of folding of the parts. These two movements are usually not combined.

One of the objects of this invention is to combine a sliding and folding action with an arrangement so that the device will mechanically fold itself without the need for manipulation by the user.

Another object of this invention is to provide an unusually large amount of expansion by reason of the sliding and folding action of the various parts which go to make up the device.

Another object of this invention is to provide a construction in which like parts are duplicates and the assembly is of duplicate arrangement whereby to reduce the expense of tools for forming the same.

Another object of this invention is to provide a resilient action which will operate either when the device is in contracted position or when in extended position so that there will be extension or contraction of the parts in accordance with strain on them or relief thereof.

Another object of this invention is to provide a maximum extension of the parts by having the folding parts overlapping each other lengthwise of the device to the full extent thereof.

With these and other objects in view, the invention consists of certain novel features of construction as will be more fully described and particularly pointed out in the appended claims.

In the accompanying drawings:

Figure 1 is a top plan view of the extension device shown as connected to links of a bracelet at either end thereof;

Figure 2 is a view similar to Fig. 1 but showing the sliding sections at the opposite ends as drawn out from the middle body section;

Figure 3 is a bottom view of the extension device alone and in contracted position;

Figure 4 is a section on line 4—4 of Figure 1;

Figure 5 is a perspective view of the various sections of the device in their extended relation so as to indicate the large amount of extensibility which is provided by the device;

Figure 6 is a longitudinal section with the device in collapsed position.

I provide a body section from which sliding sections may move beyond either end thereof. Each of the sliding sections has hinged to it two folding sections which fold beneath and nest with the sliding section, and the hinged relation of these two folding sections is such that a spring causes them to fold one upon the other into a sandwiching relation, and by providing the folding sections each of substantially the full length of the device and lying side by side widthwise of the body section, an unfolding may be had many times the length of the device.

With reference to the drawings, 10 designates the body section which has a top wall 11 and side walls 12 extending downwardly therefrom. The top wall may have a raised portion along a part of its width, as shown in Fig. 4. There is also provided inwardly extending flanges 13 from the side walls 12 so as to provide a slide-way 14 for the sliding sections 15 which extend from either end of the body section as is more clearly shown in Figs. 5 and 6.

The sliding section 15 is provided with an abutment 16 at its inner end and a spring 17 operates between this abutment 16 and the turned down finger 18 at the end of the top wall 11 of the body section 10. Thus, as the section 15 is withdrawn or slid outwardly beyond the end of the section 10, the spring 17 will be compressed and when pulling is relieved, this sliding section will slide back into the body section so as to assume the position shown in Figs. 1, 3 and 6.

A first folding section 20 is hinged to each of the sliding sections 15 by means of a pintle pin 21 which extends through eyes 22 on the section 15 and through a suitable ear 23 on the section 20. This section will fold beneath the section 15, as shown in Fig. 6, and will be suitably flanged as at 24 (see Fig. 4) so as to nest with the downwardly extending portion 25 of the section 15. Spring 26, acting about the pintle pin 21, swings the section 20 upon the pin and relative to the section 21 so that it will move to the folding relation shown in Figs. 1, 4 and 6 when a strain 45 which is placed upon the extension to hold it open as shown in Fig. 5, is relieved.

A second hinge section 28 is hinged by tongue 29 and slot 30 on the section 20 and one edge of the section 28 is provided with a flange 32 which 50 will nest with the flange 24 on the section 20, as shown in Fig. 4. There will be a sufficient frictional fit between the folding sections by reason of their flanges telescoping, as shown in Fig. 4, so as to maintain the sections in folded housed relation. The sections 20 and 28 in folded rela-

tion extend the full length of the device, as shown in the bottom view in Figure 3, and as each of the pairs of sections 20 and 28 are of a width one-half of the width of the device, they lie in side-by-side relation without increasing the thickness of the unit, and yet may be extended into position shown in Figure 5 to give a maximum extension of a chain or bracelet in which they are connected.

When the device is folded, as shown in Figure 6, the two folding sections and the sliding section may be pulled from the body housing section beyond either end thereof as is desired; or, when the folding sections are in their extended positions, as shown in Fig. 5, this action may also occur so as to enlarge the end-to-end relationship of the sections, as shown in Fig. 5.

A bracelet chain, strap or the like 35 may be attached to an eye or slot 36 in the folding sections 28 so as to provide for connecting the extension device in an encircling member of this character.

I claim:

1. An extension device for bracelets and the like comprising a body section, a pair of sliding sections guided in said body section for movement endwise in opposite directions beyond the ends of said body section, resilient means acting between said body section and said sliding sections yieldingly urging the sliding sections toward each other along the body section, a pair of folding

sections each hinged to a sliding section at its outer end, and means to connect said folding section to a bracelet or the like, the last of said folding sections being of a length to extend from the ends of the body section one beyond the other and of a width to be in side-by-side relation widthwise of the body section.

2. An extension device for bracelets and the like comprising a body section, two pairs of sections one at each end of said body section, each pair of sections consisting of two hingedly connected sections and having one section hinged to the corresponding end of said body section to fold thereunder and each pair of sections being of a length greater than one-half of the said body section, and each of a width so as to be in side-by-side relation with the corresponding section of the other pair of sections widthwise of the said body section, and means to connect the ends of the other sections of each pair of sections to the ends of a bracelet or the like.
